UNITED STATES PATENT OFFICE

BENJAMIN PUTTERMAN, OF BROOKLYN, NEW YORK, ASSIGNOR TO YANKEE METAL
PRODUCTS CORP., A CORPORATION OF NEW YORK

DESIGN FOR COMBINATION ASH TRAY AND STAND

Application filed March 30, 1932. Serial No. 43,328. Term of patent 7 years.

To all whom it may concern:

Be it known that I, BENJAMIN PUTTERMAN, a citizen of the United States of America, residing in the borough of Brooklyn, county of Kings, city and State of New York, have invented a new, original, and ornamental Design for Combination Ash Tray and Stand, of which the following is a specification, reference being had to the accompanying drawing, forming a part thereof.

This figure is a perspective of a combination ash tray and stand illustrating my new design.

I claim:

The ornamental design for a combination ash tray and stand substantially as shown.

This specification signed this 18th day of March, 1932.

BENJAMIN PUTTERMAN,
